CLAIM

The ornamental design for a collapsible wild game caller, as shown and described.

DESCRIPTION

FIG. 1 is a perspective view of a collapsible wild game caller, showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a side elevational view, the opposite side being a mirror image thereof; and,

FIG. 7 is a perspective view in the collapsed position.
